UNITED STATES PATENT OFFICE.

ROBERT V. BINGAY, OF PITTSBURGH, PENNSYLVANIA, ASSIGNOR TO PITTSBURGH TRANSFORMER COMPANY, A CORPORATION OF PENNSYLVANIA.

RADIATOR FOR TRANSFORMER TANKS.

Application filed October 1, 1920. Serial No. 414,146.

To all whom it may concern:

Be it known that I, ROBERT V. BINGAY, a citizen of the United States, residing at Pittsburgh, in the county of Allegheny and State of Pennsylvania, have invented certain new and useful Improvements in Radiators for Transformer Tanks, of which the following is a specification.

This invention relates to electrical apparatus cooled by a circulating fluid such as oil which in turn is cooled by the surrounding air. In such self-cooled apparatus, for instance transformers, it is often necessary to provide special radiating means in addition to the tank surfaces to give a sufficient area of contact with the atmosphere. The chief object of this invention is to provide a simple, inexpensive radiator adapted to be carried on the side of the transformer tank and connected with the oil circulation so that the heated oil will pass through the radiator and be cooled thereby.

A further object of the invention is to provide a radiator which may be opened for inspection and readily cleaned throughout.

In the accompanying drawings illustrating the invention—

Figs. 1 and 2 are elevational views of a radiator embodying the invention, and

Fig. 3 is a horizontal sectional view on line 3—3 of Fig. 1.

In the specific embodiment of the invention illustrated in the drawings a transformer tank T carries the radiators R each of which is connected to the tank through the upper pipe 5 for the hot oil and the lower pipe 6 for the cooled oil. The lower pipe 6 is provided with a three-way valve 7 which may be turned to close pipe 6 or open connection between the radiator and the tank, or between the radiator and the discharge pipe 9 extending from the pipe 6. By this means the radiator may be either connected or disconnected and when disconnected may be open through the lower outlet pipe 9 for emptying.

The radiator R comprises upper and lower headers 10 and 11 and between these headers extend the radiating pipes 15 forming cooling conduits connected between the headers. In the operation of the transformer the heated oil going out through pipe 5 into header 10 is distributed among the pipes 15 and flows downwardly through the header

11 to the pipe 6 to the bottom of the transformer tank T.

The transformer cooling oil sometimes deteriorates in practice and tends to become viscous, so that the hot oil on being cooled in the pipes 15 deposits a heat insulating film on the interior of the radiating surfaces seriously interfering with the radiation of the heat and obstructing the flow so that a restricted quantity of only partially cooled oil reaches the lower header 11. This in turn causes a rise in the temperature of the transformer oil with consequent further deterioration and these conditions are accumulative causing dangerous overheating of the transformer. To prevent this objectionable deposit and stoppage of the flow the radiators R are provided with removable covers 20 for the upper headers 10 and similar bottom plates may be provided for the lower headers 11 instead of the closed bottoms 21 as shown. To provide for the removable cover 20 the top header 10 is flanged over at 23 and the cover 20 is fitted over this flange 23 with a gasket 24 in between. Clamps 25 are bolted to the edge of the cover 20 and extending under the flange 23 firmly press or pinch the flange and cover together when the clamping bolts are tightened. These clamps 25 are easily released to permit removal of the cover by simply loosening the clamping bolts. With the valve 7 then turned to close pipe 6 and open connection between the header 11 and discharge 9 the radiator R will be emptied and its pipes will be accessible for inspection and cleaning. After this the cover 20 is replaced and valve 7 turned to reopen connection between the radiator and the lower part of the tank, the necessary oil being replaced in the main tank.

The radiator of this invention may be made of any suitable metal parts. It may for instance be made of steel throughout, the tubes 15 being simply ordinary pipes welded into the headers 10 and 11 at each end, and the whole being light and at the same time strong and durable. The easy accessibility of the cooling tubes for inspection and cleaning saves in cost of repair and replacement and keeps the transformer in operation by encouraging the operator to make frequent inspections. By adding shut off valves to the pipes 5 a transformer hav-

ing a plurality of radiators may be kept in operation while one radiator at a time is shut off and inspected and drained, and cleaned. The valve 7 intervenes between the 5 tank T and the radiator connection 26 and the same would be true of the valve in the upper pipe 5, so that the radiators R may be connected in place or disconnected without emptying the tank T. This is particularly advantageous in case it is necessary to 10 remove the radiator from the tank for repair and where the tank T is too large to be shipped with the radiators in place. In such cases the radiator valves will be closed 15 and the radiators removed and then replaced without emptying or refilling the tank which are troublesome operations and likely to result in adding impurities and moisture to the oil. While the invention

has been shown in connection with a specific 20 embodiment it is not confined thereto but is intended to cover such modifications as fall within the scope of the appended claim.

I claim:

The combination with a transformer tank 25 of a plurality of detachable radiators therefor comprising upper and lower headers and connecting pipes, a connection from the tank to the upper header below the top thereof, the top of said header being removable to permit access to all of said pipes 30 and means between the radiators and tank to allow draining of the radiator independently of said tank, said means being also adapted to prevent draining of the tank 35 on removal of the radiator.

ROBERT V. BINGAY.
